DESIGN FOR A NIGHTGOWN

Irving Lieberman, New York, N. Y.

Application April 16, 1936, Serial No. 62,157

Term of patent 3½ years

To all whom it may concern:

Be it known that I, Irving Lieberman, a citizen of the United States of America, residing in Manhattan, county of New York, and State of New York, have invented a new, original, and ornamental Design for a Nightgown, of which the following is a specification, reference being had to the accompanying drawing, forming part thereof, wherein,

I claim:

The ornamental design for a nightgown, substantially as shown.

IRVING LIEBERMAN.
